INVENTOR,

UNITED STATES PATENT OFFICE.

GEORGE WASHINGTON JORY, OF MARYSVILLE, CALIFORNIA.

DITCHER AND GRADER.

1,146,261.

Specification of Letters Patent. Patented July 13, 1915.

Application filed April 9, 1913. Serial No. 760,006.

To all whom it may concern:

Be it known that I, GEORGE W. JORY, a citizen of the United States, residing at Marysville, in the county of Yuba and State 5 of California, have invented a new and useful Ditcher and Grader, of which the following is a specification.

This invention has reference to improvements in machines for ditching and grading, 10 loading vehicles and the like, and its object is to provide a machine which by progressive movement along the surface of the ground may be caused to either excavate a ditch in the ground or to remove a small 15 depth of earth for grading purposes, the removed earth in either case being deposited in a series of buckets mounted on the machine to rotate on an axis at an angle to the vertical, whereby one edge of the bucket 20 series is brought into contact with the ground while the opposite edge is elevated. A machine of such character is shown and described in Letters Patent No. 1,028,734, granted to me on June 4, 1912, for improvements 25 in ditchers and graders, and the present invention has to do with certain features of such a machine whereby certain improved results are obtained.

The present invention has to do with a 30 construction whereby the machine may be employed on inclines either already existing or due to the previous action of the machine, without tilting certain parts which advantageously remain upright.

The invention has also to do with improved means for applying the draft to the 35 machine and moving the same in curved paths; with means for adjusting the supporting wheels of the machine; to an improved 40 bucket construction; to improved means for causing the rotation of the circular series of buckets by the progressive movement of the machine; to means for preparing the ground in advance of a plow; to means for causing 45 the plow to deliver upon the buckets, and to means for directing the excavated dirt elevated by the buckets to such a distance from the excavator as may be found advisable, and also to means for closing the buckets, all 50 the devices being carried by and forming parts of the excavator as a whole.

The invention will be best understood from a consideration of the following detailed description, taken in connection with

the accompanying drawings forming a part 55 of this specification, with the further understanding that while the drawings show a practical embodiment of the invention the latter is not confined to any strict conformity with the showing of the drawings, but may 60 be changed and modified so long as such changes and modifications mark no material departure from the salient features of the invention.

In the drawings:—Figure 1 is a plan view 65 of the improved machine. Fig. 2 is a section on the line 2—2 of Fig. 1. Fig. 3 is a section on the line 3—3 of Fig. 1, with parts omitted. Fig. 4 is a bottom plan view of the discharge scoop. Fig. 5 is a section on 70 the line 5—5 of Fig. 4. Fig. 6 is a detail side elevation of a clod crusher attachment. Fig. 7 is an end elevation thereof with a portion of the supporting frame of the machine 75 in cross section. Fig. 8 is a detail plan view of a portion of the machine carrying the plow. Fig. 9 is a side elevation of the structure shown in Fig. 8. Fig. 10 is a detail 80 sectional view of a part of the frame adjusting device.

The machine is provided with a main longitudinal beam 1, a reach 2 spaced from and parallel with the beam 1, and end bars 3, 4, respectively, the end bars being secured by clips 5 or by other suitable devices to the 85 ends of the reach, while the end bars are each connected to the beam 1 by straps 6 and a plate 7 hinged together as indicated at 8, the plate 7 being firmly united to the beam 1. In the particular structure shown and 90 considering the end bars 3 and 4 as horizontal, the beam 1 is more elevated than the corresponding end of the end bars and the reach 2 is below the corresponding ends of the end bars. The purpose of hinging the 95 end bars 3 and 4 to the main beam 1 is to permit that side of the frame where the reach 2 is located being tilted with respect to the beam 1, so that the reach side of the machine may ride on an elevation or the 100 beam 1 may be in a depression or excavation without the necessity of the beam 1 being tilted in conformity with the lateral slope of the ground with respect to the travel of the machine.

The beam 1 is supported near the ends by wheels 9, 10, respectively, while at an intermediate point the reach 2 is supported by a

wheel 11, these different wheels being arranged for certain adjustments to be described.

Each plate 7 is extended above the beam 1 and there has journalled in it one end of a rod 12, the other end 13 of which is screw-threaded and extends through a nut 14 in a shoulder 15 secured to the respective end beam 2 or 3, this last structure being best shown in Fig. 10.

Adjacent to the plate 7 each rod 12 carries a sprocket wheel 16 held in place by a set screw 17, while the end of the rod is projected through the corresponding portion of the plate 7 and is there held as shown at 18 or otherwise formed so that while the rod may turn in the plate 17 as a bearing, it will not move lengthwise thereof. The two sprocket wheels 16 are connected by a sprocket chain 19. One of the rods 12 may be continued beyond the head 18 and provided with a crank handle 20, by means of which the two rods may be turned simultaneously to screw them into or out of the nut 14, thus decreasing or increasing the effective length of the rods, and so changing the angular relation of the beam 1 and the end beams 3 and parts carried thereby about the hinges 8. This change of angular relation may very readily be performed, while the machine is in operation.

The wheel 9 is mounted upon an angle extension 21 of an arbor 22, the angle of the extension to the arbor being somewhat greater than ninety degrees, so that with the arbor upright the wheel 9 is tilted, and its upper edge is toward the reach 2. The arbor 22 is slidably and rotatably supported in a bearing block 23 bolted or otherwise secured to the beam 1 and the arbor 22 extends above the bearing 23 and the beam 1 and at the upper end carries an arm 24. The bearing 23 is on the reach side of the beam 1, while the arm 24 extends in a direction away from the reach 2 or in a direction away from the angle extension 21. Rising from the beam 1 at the front end thereof is a link 25 pivoted at the lower end to the beam and at the upper end pivotally connected to one end of an adjusting lever 26. The point of connection between the lever 26 and link 25 may be varied by providing a series of holes 27 in the link by means of which the lever may be connected to it at different points. The lever 26 has a swivel connection 28 with the arm 24 close to the arbor 22, while the other end of the lever, which latter may extend rearwardly for an appropriate distance, is movable along an adjusting rack segment 29 with which it may be held in engagement by a thumb latch 30.

The wheel 10 is mounted on an arbor 31 like the arbor 22, but instead of this arbor being mounted on the inner face of the beam 1 it is mounted near the rear end thereof at

a point intermediate of the beam in a suitable bearing 32 and at the upper end the arbor carries an arm 33 like the arm 24 except that it projects toward the reach 2 or in the same general direction as the wheel 70 carrying spindle at the lower end of the arbor, this spindle being indicated at 34 and has the same general angular relation to the arbor 31 as does the angular extension or spindle 21 with respect to the arbor 22. At 75 the rear end of the beam 1 there is provided a link 35 like the link 25 and this link is pivoted to the rear end of the beam at the lower end and at the upper end is pivotally connected to one end of a lever 36, the link 80 being provided with adjusting perforations 37 like the link 25. Moreover, the lever 36 has a swivel connection 38 with the arm 31 and this lever projects forwardly in operative relation to a rack segment 39 with which 35 it may be engaged in different positions of adjustment by a thumb latch 40.

The outer end of the arm 24 is connected by a rod 41 with an adjusting hand lever 42 rising from a bar 43 to which it is pivoted, and also provided with a thumb latch structure 44 in operative relation to a rack segment 45 carried by the bar 43. The outer end of the arm 33 is connected by a rod 46 to an adjusting lever 47 mounted on a bar 48 provided with a thumb latch structure 49 in operative relation to a rack segment 50 also mounted on the bar 48. The two bars 43 and 48 are carried by clips 51, 52, respectively, fast to the beam 1 about midway 100 of its length so as to slide lengthwise of the beam 1, and these bars may, if desired, be coupled together by a hook 53, so that on the application of a suitable force the bars 43 and 48 may be moved simultaneously, or the 105 bar 43 be moved alone lengthwise of the beam 1, and this movement will cause corresponding movements of the arms 24, or 24 and 33 to rotate the arbor 22 or the two arbors 22 and 31, and when the two arbors 110 are moved simultaneously they rotate in opposite directions. When the bar 43 is moved alone then the hook 53 may be engaged in an eye 53a fast to the beam 1, thus holding the bar 48 firmly against movement.

At appropriately spaced points two brace rods 54 are connected to the front beam 3, and these rods extend forwardly and one toward the other, and are at their front ends connected to a block or support 55 in which is pivoted a bar 56 extending forwardly for attachment to power and rearwardly to the end beam 3 where the bar is narrowed, as shown at 57 to engage in notches 58 in a rack plate 59. The adjustment of the bar 120 56 provides a means for ready equalization of the draft.

Pivoted to the front end of the bar 56 is an angle lever 60 to which the draft is directly connected, and this lever is connected 125

by a link 61 to one end of a bar 62 having the said end formed as shown at 63 to slide in a stirrup 64. The other end of the bar 62 is carried to and is pivotally connected 5 to the bar 43. The arrangement is such that when the draft lever 60 is in an intermediate position the wheels 9 and 10 are parallel with the beam 1, but should the lever 60 be moved in its pivot support to one side or 10 the other of the center line, then the angle lever 60 causes a longitudinal movement of the link 61 and rod 62 which is communicated to the bar 43 and if the bars 43 and 48 be connected, then this movement is further 15 communicated by way of the levers 42 and 47 to the respective links 41 and 46 and by the latter to the arms 24 and 33, thus oppositely rotating the arbors 22 and 31 to adjust the wheels 9 and 10 to travel in a 20 curved path, the center of which is to one side or the other of the beam 1 in accordance with the adjustment of the draft. The connections between the levers 26 and 36 and the respective arms 24 and 33 are sufficiently 25 loose to permit of the movements of said arms in accordance with the adjustment of the draft and the latches on the levers 26 and 36 are so arranged as to allow slight end play of the levers on their respective 30 racks.

A seat 65 may be conveniently mounted upon the bar 56 and a platform 66 may be secured to the beam 1 for the support of an operator having to manipulate the levers 26, 35 36, 42 and 47. Furthermore, the end beams 3 and 4 are attached to the beam 1 by braces 67, whereby the structure may be made rigid so far as the draft strains are concerned.

Erected on the reach 2 about midway of 40 its length is a post 68 set at an incline toward the beam 1. The upper end of this post may be braced to the connected ends of the reach and end bars by stay rods 69 and the inclination of the post may be varied 45 by a lever 70 having one end connected to the post near the upper end thereof and the other end reaching to the beam 1 which it overhangs, and there movable in operative relation to an upright rack bar 71 for holding 50 the lever 70 in adjusted positions.

Mounted on the post 68 is an elongated sleeve 72 from which spread arms 73 with a downward inclination to a rim 74, each arm being connected to the sleeve 72 at a 55 distance from the arms 73 by brace rods 75, the arms 73, rim 74, and brace rods 75, together with the sleeve 72 constituting a spider for a circular series of dirt receiving buckets all of which in general construction 60 may be similar to like parts shown and described in the aforesaid Letters Patent, and so requiring no particular description herein. The outer ends of the arms 73 are reduced in diameter and extended radially 65 outward, as indicated at 76, and at their

outer ends are connected to and carry a rim 77 substantially parallel with the rim 74, the two rims 74 and 77 rising from the extensions 76. Moreover lugs 78 are carried by the rim 77 or extensions 76 or both, being 70 preferably formed of angle iron, and are arranged in depending relation to the rim 77.

The space between the rims 74 and 77 is filled up with a circular series of buckets each composed of a bottom plate 79 and one end plate 80 and the bottom plates have intermediate hinge connections 81 with the respective extensions 76. The bottom plates 79 are substantially segmental, since the inner rim 74 may be polygonal and the outer rim 77 may be circular. The arrangement of the buckets is such that in the rotation of the spider in a manner to be described the end plates or partitions 80 are uppermost on the rising run. The buckets are held in 85 the closed position by latch fingers 82 arranged to engage between lugs 82^a on the inner rim 74. The buckets are released at the proper time by a roller 82^b on the end of a rod 82^c fast to the axial support of the 90 bucket carrier. In order to close the buckets a roller 82^d is provided in the outer end of a rod 82^c, while a curved strip 82^e on the same rod urges the bucket toward the closed position as it approaches the roller 82^d. The 95 opening and closing devices just described may be, and as shown are similar to corresponding parts shown and described in the aforesaid Letters Patent. However, it may at times transpire that the buckets do not 100 become positively latched, wherefore there is mounted on the reach a rod or bar 83 in the path of the descending run of the buckets should any of these buckets be in the open position and so arranged that the buckets will become positively closed by the auxiliary closing device 83 if needed.

Mounted on the inclined post 68 is an arm 84 under-riding the rotary elevator and extending over the wheel 11 toward the highest point of travel of the rotary elevator. The arm 84 may be tubular, and at the outer end receives the stem 85 of a T bracket 86 having oppositely extended members projecting through eyes 87 on the under face of 110 a chute 88, which latter may be in the form of a plate with upturned ends. This chute is so located as to underride the upper run of the buckets where they are released for dumping to receive the earth gravitating 115 from the buckets and the chute is controlled by a chain 89 fast at one end to the chute and at the other end adjustably secured to the stem 85, so that the chute is set at an incline directing dirt deposited upon it in a 120 direction away from the reach 2. The degree of throw of the dirt from the chute may be regulated by tilting the chute more or less as needed. By providing the outer end of the arm 84 with a clip 90 the stem 85 may 125 130

be adjusted lengthwise of the arm to regulate the position of the chute with relation to the dumping position of the buckets.

At about midway of the length of the beam 1 adjacent which point the inclined rotatable series of buckets engages the ground, there is depending from the beam a yoke 91 having an offset intermediate connecting member 92 in underriding relation to the beam, while the legs of this yoke may be bolted or otherwise secured to the beam. Journaled on the offset portion 92 of the yoke is a disk plow 93 which may be taken as indicative of any suitable means for engaging the ground and directing it into the buckets as they pass adjacent to the plow, and in this respect the structure of the present invention is similar to that disclosed in the aforesaid Letters Patent. The braces 67 may be connected to the yoke 91 by brackets 94 to which the braces are pivotally connected as indicated at 95, thus permitting the adjustments of the end beams 3 and 4 and main beam 1 with respect one to the other.

Trailing behind the inner edge of the plow is a plate or share 96, at the lower end of a suitably bent bar 97 overhanging the plow 93 and carried forward beyond the front end 30 of the yoke 91 where this bar is bent, as indicated at 98, and is mounted in spaced brackets 99. The plate or share 96 is set at an angle to the line of travel of the machine in a manner to overhang the upper edge of 35 the lower run of the series of buckets to thereby direct dirt from the plow into said buckets.

Under certain conditions the plow will lift into the buckets clods of dirt too large to 40 pass through the opening between the buckets when the latter dump. To overcome this difficulty there is mounted on the beam 1 at an appropriate distance in front of the plow a slideable bar 100 held to the beam by overhanging guide strips 101. This bar 100 is upright and at the upper side of the beam 1 has a hand lever 102 fast thereto at an intermediate point of the hand lever, and one end of the hand lever is connected by a link 103 to one of the guides 101 while rising from the other guide 101 is a rack bar 104 in position to be engaged by a thumb latch 105 on the adjusting lever 102. The lower end of the bar 100 below the beam 1 is formed into 55 a yoke 106 in which is journaled a rotary cutter 107 having an appropriate number of cutting blades 108 outstanding therefrom. This cutter 107 is located in front of the plow so as to attack the ground and cut the sod into sufficiently small pieces before 60 reaching the plow to prevent clogging of the buckets.

With a machine constructed as described, or with the main beam, end beams or bars 65 and reach made of structural steel, it may

be assumed that the ditcher is being drawn along by horses or other suitable means with the lower run of the rotatable circular series of buckets engaging the ground, which latter may be assumed to be level, and the parts 70 are so adjusted that the projections or lugs 78 will enter the ground sufficiently to impart rotative movement of the series of buckets as the machine progresses. The wheels 9 and 10 are adjusted to cause the proper engagement 75 of the rotatable series of buckets with the ground, and the plow is so related to the rotatable series of buckets that when the latter are in engagement with the ground the plow enters the ground sufficiently to 80 lift dirt therefrom and leave a furrow caused by the excavation of the dirt and its deposition in the buckets, this deposition of the dirt taking place continuously as the vehicle advances and the series of buckets 85 being rotated continuously by the advance of the vehicle. Furthermore, the cutter 107 is suitably adjusted to divide the sod into small pieces in advance of the plow.

As the dirt is deposited in the buckets and 90 the filled buckets move away from the receiving point, they are continuously elevated until they reach a point diametrically opposite from the receiving point, and there they are at the highest point of travel, 95 whereupon the buckets are tripped in a manner shown and described in the aforesaid letters patent or in any other suitable manner, and that end of each bucket having the end plate 80 is elevated so that the contents of the bucket readily escape by gravity, and since there are no fixed partitions between the buckets the capacity of the conveyer is correspondingly increased and the size of the discharge openings caused by the 100 tilting of the buckets is enlarged. The gravitating earth from the tilted buckets strikes upon the deflector chute 88 and is thereby directed farther away from the machine than would be the case were the chute 110 absent and may deposit the dirt into a wagon. On the lowering run of the buckets they are closed by any suitable mechanism such as shown and described in the aforesaid letters patent, but should it transpire that a bucket is not properly closed, the positive closure of the bucket is assured by the auxiliary member 83, thus preventing the buckets catching in the ground on the down run.

If the ditch or the grading is not in a straight path then the lever 60 shifts to one side or the other of the center line of draft, so that the pull of the machine is no longer directly longitudinal thereof, but tends to 125 move the machine in a curved path and this is facilitated by the wheels 9 and 10, or the wheel 9 alone, one or both of which are turned correspondingly to the shifting of the angle extension of the lever 60, acting 130

through the link 61 and rod 62 upon the bar 43 and by way of the latter through the link 41 to the arm 24 and spindle 22, and if the bar 48 is connected to the bar 43 then the wheel 10 is turned to an appropriate angle to the center line of the machine to follow the curved path of the machine. Both wheels 9 and 10 are furrow wheels and may be shifted automatically or independently as may be desired. Both of these wheels may likewise be adjusted with respect to the beam 1 so that the latter may be depressed or elevated to cause the engagement of the plow and buckets with the ground being acted upon, or these parts may be lifted sufficiently to render them inactive as when the machine is being transported from place to place.

When the machine is used for producing ditches the ditch is deepened by passing over the same path a suitable number of times, and then the wheels 9 and 10 are lower than the wheel 11, so that the whole machine is tilted correspondingly and in the absence of suitable provision for compensating the tilting, those parts carried by the beam 1 would be likewise tilted. Therefore, as the ditch is deepened the threaded rods 12 may be turned in a manner to screw them through the nuts 14 to shorten their effective length, wherefore the beam 1 is rocked on the hinges 8 toward the beams 3 and 4, so that the angular relation of these parts is changed in a manner to maintain the parts carried by the beam 1 upright even though the wheels 9 and 10 be running in a deepening furrow, and the wheel 11 be running upon a relatively elevated portion of the surface. Again, when the machine is running on ground which is not level it may be adjusted so that the effect of want of level is overcome, this adjustment being brought about by a proper manipulation of the rods 12.

45. What is claimed is:—

1. In an excavating machine, an inclined rotatable member having an outer circumferential wall consisting of an upstanding rim, lugs on and in depending relation thereto, an inner wall or upstanding rim spaced from the outer rim, arms carrying the inner rim and provided with reduced extensions carrying the outer rim and spacing the latter from the inner rim, and buckets between the rims and hingedly mounted directly on the reduced extensions of the arms.

2. In an excavating machine, an inclined rotatable member having inner and outer walls spaced apart, arms carrying the inner wall and provided with reduced extensions to the outer wall at the lower margins of the walls, said reduced extensions spacing the inner and outer walls apart and constituting connecting devices therebetween, and a series of buckets hinged to the reduced exten-

sions of the arms between the walls and each comprising a bottom member and a single end member in turn constituting a division wall between the bucket carrying it and the next adjacent bucket, the hinge connection 70 between the bucket and the reduced extension of the arm carrying it being located intermediate of said bottom member.

3. In an excavating machine, an inclined rotatable member having inner and outer walls spaced apart with connecting devices between the lower margins of the walls, said connecting devices being spaced circumferentially, and a series of buckets comprising bottom members intermediately hinged to 75 the connecting devices, and a single end member for each bottom member constituting division walls between the buckets movable with the bottom members.

4. In an excavating machine, an inclined 85 rotatable series of dirt receiving buckets or receptacles each comprising a bottom member and one end member, each end member carried by the bottom member constituting an end member for the next preceding 90 bucket.

5. In an excavating machine, an inclined rotatable series of dirt receiving buckets or receptacles with one edge in position to engage the ground and provided with an outer 95 upstanding rim, a plow in operative relation to the series of buckets where engaging the ground, and a deflector plate in trailing relation to the plow and also inclined to the line of travel and elevated to a height to deflect dirt lifted by the plow into the buckets over the rim of the series of buckets, said plate being provided with a yieldable support 100 separate from the plow to conform to variations in the relative up and down 105 movements of the plow and the series of buckets.

6. In an excavating machine, an inclined rotatable series of dirt receiving buckets or receptacles with one edge in position to engage the ground and provided with an outer upstanding rim, a plow in operative relation to the series of buckets where engaging the ground, and a deflector plate in trailing relation to the plow and also inclined to the line 110 of travel and elevated to a height to deflect dirt lifted by the plow into the buckets over the rim of the series of buckets, said plate being provided with a yieldable support 115 separate from the plow to conform to variations in the relative up and down movements of the plow and the series of buckets, and said yieldable support being located in over- 120 riding relation to the plow.

7. In an excavating machine, an inclined 125 rotatable series of dirt receiving buckets or receptacles with an outer upstanding rim in position to engage the ground, a plow mechanism in operative relation to the series of buckets engaging the ground, and a de- 130

5 reflector plate or share in operative relation to the plow and inclined to the line of draft and at an elevation with respect to the ground to direct dirt from the plow over the 5 rim of the series of buckets into such buckets, and said plate or share being yieldably mounted for up and down movements.

8. In an excavating machine, a hinged frame having the hinge axis longitudinal of 10 and at the furrow side of the machine, lifting dirt receiving means mounted on one section of the machine, a plow mounted on the other section of the machine, and means for varying the angle of one part of the 15 frame of the machine to the other about the axis of said hinge connection.

9. In an excavating machine, a frame provided with intermediately located dirt excavating means at the furrow side and with 20 furrow wheels at opposite ends, a mounting for each wheel movable longitudinally and rotatably with respect to the frame, means for adjusting the mounting longitudinally and other means for adjusting the mounting 25 rotatably, both adjusting means being provided with locking means for holding them in adjusted positions.

10. In a ditching machine, a frame, furrow wheels mounted at opposite ends of the 30 frame and provided with spindles each rotatable on its longitudinal axis with reference to the frame and carrying the wheel at an angle to such longitudinal axis, an angle arm on each spindle, an adjusting means for 35 each angle arm, a slidable member carrying the adjusting means, an actuating means for one of the slidable members, and means for connecting the other slidable member to the first-named slidable member for causing simultaneous movement thereof.

11. In a ditching machine, a frame, furrow wheels mounted at opposite ends of the frame and provided with spindles each rotatable on its longitudinal axis with reference to the frame and carrying the wheel at an angle to such longitudinal axis, an angle arm on each spindle, an adjusting means for each angle arm, a slidable member carrying adjusting means, an actuating means for one 50 of the slidable members, and means for connecting the other slidable member to the first named slidable member for causing simultaneous movement thereof, the connecting means being constructed for disconnection 55 from the other slidable member and the frame being provided with means for receiving the connecting means when disconnected from the other slidable member.

12. In an excavating machine, a furrow 60 wheel, a relatively upright member carrying the furrow wheel and mounted for both rotative and longitudinal movements, the upright member being provided with a laterally projecting arm at the end remote from 65 the furrow wheel, an adjusting lever for

causing longitudinal movements of the upright member, and an adjustable connection with the arm for causing rotative movements of the supporting member of the furrow wheel.

70 13. In an excavating machine, a furrow wheel, a relatively upright member carrying the furrow wheel and mounted for both rotative and longitudinal movements, the upright member being provided with a laterally projecting arm at the end remote from the furrow wheel, an adjusting lever for causing longitudinal movements of the upright member, and an adjustable connection with the arm for causing rotative movements of the supporting member of the furrow wheel, the last named adjusting means having a slidable support for causing rotative movements of the upright member carrying the furrow wheel independently of the 80 first named adjusting means therefor.

75 14. In an excavating machine, a frame composed of a main beam, a reach in parallel relation thereto and end beams each fast at one end to the reach and at the other 90 end having a hinge connection with the main beam, threaded adjusting rods carried by the main beam, threaded receptacles for the rods carried by the end beams, and connections between the rods for rotating them simultaneously to adjust the angular relation of the portion of the frame composed of the end beams and reach to the main beam.

85 15. An excavating machine provided with a main frame composed of a longitudinal beam, a reach in parallel relation thereto, and end beams each connected at one end to the reach end at the other end having a hinge connection with the main beam, an inclined rotatable series of buckets carried by the portion of the frame composed of the reach and end beams, a supporting wheel on the same part of the frame carrying the rotatable series of buckets, furrow wheels carried by the main beam, and adjusting connections between the main beam and the end beams and connected for simultaneous movement to adjust the angular relation of the end beams and main beam.

90 16. An excavating machine provided with a main frame composed of a longitudinal beam, a reach in parallel relation thereto, and end beams each connected at one end to the reach and at the other end having a hinge connection with the main beam, an inclined rotatable series of buckets carried by the portion of the frame composed of the reach and end beams, a supporting wheel on the same part of the frame carrying the rotatable series of buckets, furrow wheels carried by the main beam, and adjusting connections between the main beam and the end beams and connected for simultaneous movement to adjust the angular relation of the end beams and main 105 beam.

beam, said adjusting connections comprising screw rods having journal supports on the main beam, nuts on the end beams traversed by the threaded rods, and connections 5 between the threaded rods for rotating them simultaneously in either direction.

17. In a ditching machine, an inclined rotatable series of dirt receptacles or buckets, an inclined axial support for said series of 10 buckets, an arm carried by the axial support and projecting therefrom in underriding relation to the buckets to the discharge point of the latter, a chute, a support for the chute carried by and adjustable longitudinally 15 along the arm at the outer end of the latter, the chute being hingedly connected to its longitudinally adjustable support, and holding means for the chute adjustable to vary its inclination.

20. 18. In a ditching machine provided with an inclined rotatable series of dumping

buckets and means for opening and closing the buckets, a supplemental bucket closing device located in operative relation to the descending run of the series. 25

19. In a ditching machine provided with an inclined rotatable series of dumping buckets and means for opening and closing said buckets, a supplemental closing device located in operative relation to the descending run of the series and comprising a rod or bar on a relatively fixed portion of the machine in underriding relation to the descending run of the buckets. 30

In testimony, that I claim the foregoing 35 as my own, I have hereto affixed my signature in the presence of two witnesses.

GEORGE WASHINGTON JORY.

Witnesses:

HARRY OSBORN,
RICHARD BEECHER.
